Patrick O'Neill and Patrick Joseph Douglas, Dungannon,
Northern Ireland, assignors to Powerscreen Interna-
tional Limited, Dungannon, Northern Ireland

Filed Mar. 14, 1973, Ser. No. 341,257

Claims priority, application Great Britain Aug. 26, 1972

Term of patent 14 years

Int. Cl. D12—05

U.S. Cl. D55—1 C

FIG. 1

FIG.3.

FIG. 1 is a side elevation of an articulated conveyor unit showing our new design;

FIG. 2 is a plan view; and

FIG. 3 is an end view in the direction of the arrow 3 of FIG. 1.

We claim:

The ornamental design for an articulated conveyor unit, substantially as shown and described.
